UNITED STATES PATENT OFFICE.

FREDERICK W. ALBRECHT, OF TOLEDO, OHIO, ASSIGNOR OF ONE-HALF TO CHARLES H. SHIELDS, OF TOLEDO, OHIO.

WORK GAGING AND HOLDING MEANS.

1,023,407.

Specification of Letters Patent.

Patented Apr. 16, 1912.

Application filed April 27, 1911. Serial No. 623,790.

To all whom it may concern:

Be it known that I, FREDERICK W. ALBRECHT, a citizen of the United States, and a resident of Toledo, in the county of Lucas and State of Ohio, have invented a certain new and useful Work Gaging and Holding Means; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to means for gaging the position of and holding materials preparatory to cutting or otherwise acting thereon, and while it has particular reference to use in printing offices for use in connection with machines for the cutting and trimming of slugs, cuts or the like, it may be used in any other connection for which it may be adapted or appropriate.

The object of my invention is the provision in an apparatus of this character of simple and improved gage adjusting means for permitting an easy, quick and accurate adjustment of the gage-block as the measurement desired may require.

A further object of my invention is the provision of simple, improved and easily operated means for clamping the work to be acted on, whereby to enhance the practicability and commercial value of apparatus of this class.

The invention is fully described in the following specification, and while, in its broader aspect, it is capable of embodiment in numerous forms, a preferred embodiment thereof is illustrated in the accompanying drawings, in which,—

Figure 1 is a plan view of an apparatus embodying my invention with parts of the same broken away. Fig. 2 is a front side view thereof. Fig. 3 is an end view thereof. Figs. 4, 5 and 6 are sections on the lines 4—4, 5—5 and 6—6, respectively, in Fig. 1.

Referring to the drawings, 1 designates a table, plate, or other suitable part, upon which the mechanism comprising my invention may be mounted. This table, if it is desired to move the work which is clamped thereto, as hereinafter described, to a saw,

knife or other trimming member with which it may be associated, may be suitably mounted for reciprocatory movements on the frame or top of a machine or other apparatus to which it may be attached. As the invention consists in the gage block adjusting feature and in the work clamping means for use in any connection for which they are adapted, they are not shown in connection with any particular machine.

Fixed to the top of the table 1, in the present instance transversely thereof, is a guide-bar 2 which is provided on its top longitudinally thereof with a series of diagonally disposed threads, 3, which, if the apparatus is to be used in a printing office in connection with the cutting of slugs, cuts or the like, preferably measure one pica from center to center thereof longitudinally of the guide-bar. The bar 2 is preferably graduated on its top adjacent one edge thereof to designate picas or other units of measurement, as indicated in Fig. 1.

The gage block 4 of the apparatus is provided on its under side with a transverse groove or recess 6 of suitable size to fit closely over the guide-bar 2 to permit the gage-block 4 to be moved longitudinally thereof or to be raised from engagement therewith, as desired. The head 5 of the gage-block is provided in its top longitudinally of the block with a recess 7, which opens into the groove 6 of the block. Closing the end portions of the recess 7 and rising above the top of the head 5 are bearing bosses 8 and 9 through which a micrometer adjusting screw 10 projects and has its bearings. The bearing opening in the boss 8 is of suitable size to receive a cylindrical enlargement 11 at the head end of the screw 10, at the outer end of which enlargement is formed a screw head 12, which is preferably knurled to facilitate a turning of the same. In the bearing opening of the outer boss 9 is threaded a bushing 13 in which the outer ends of the screw 10 is journaled, as best shown in Fig. 4.

The screw 10 is prevented from having longitudinal movements within its bushing 13 by a pin 14, which projects axially through the screw and has one end provided with a head 15 for abutting against the outer end of the screw and overlapping the outer

end of the bushing 13 to coöperate with a shoulder 16 on the screw to prevent longitudinal movements of the screw within the bushing, while the other end of the pin 14 5 has a nut 17 threaded thereto without the headed end of the screw, as shown. The screw 10 is threaded through a nut 18, which fits within the recess 7 for longitudinal movements therein and has its under side 10 provided with teeth 19 of suitable form for meshing with the teeth 3 on the guide bar 2. To adjust the screw 10 longitudinally within the boss bearings, it is only necessary to turn the bushing 13 for such purpose. 15 It is apparent with this construction that a turning of the adjusting screw 10 will impart movement to the nut 18 transversely of the bar 2 and effect a consequent adjustment of the gage-block 4 relative to the 20 bar 2, due to the coöperating action of the nut and bar teeth during such movement. The threads of the screw 10 are preferably of such pitch that a complete turn of the screw within the nut 18 will move the nut 25 a sufficient distance transversely of the bar 2 to move the gage-block a distance equal to one pica or other unit of measurement for which the threads may be adapted. The enlarged portion 11 of the screw is preferably 30 provided therearound with a series of recesses 11' with which a spring pressed detent 20 which is mounted in a socket 21 in the gage-block is adapted to engage to yieldingly resist a turning of the screw at 35 predetermined points in a revolution thereof to indicate nonpareils or other fractional points of adjustment of the units of measurement used. The enlargement 11 may also, if desired, be provided with graduations for registering with a fixed point on the boss 8 to indicate the degree of turning of the same. 40

With the gage adjusting mechanism above described a rapid and accurate adjustment of the gage-block is possible, as a quick movement of the block from one unit designation to another can be obtained by raising the block sufficiently to disengage the threads of the nut 18 from those 45 of the guide-bar 2, after which the gage-block can be moved to any desired position of unit adjustment and then lowered to engage the nut threads with those of the bar. If it is then desired to secure an adjustment of the gage-block which is fractional to the unit designations, the adjusting screw 10 is turned until the inner edge of the gage block has reached, the desired 50 position intermediate the unit designations. 55

As, for instance, should it be desired to cut a piece into a length equal to 10 picas and 3 points, the gage-block is placed with its inner edge in register with either the 10 or the 11 pica mark and the screw 10 is 60 then turned to move the nut 18 in the proper

direction to place the gage-block edge at the desired position intermediate said pica marks, as is apparent.

The means employed for clamping the work while being cut or otherwise acted on 70 comprises a clamping-block or finger 22, which is fixed to and movable with a longitudinally shiftable bar 23 one end portion of which is slidably mounted in a block 24, which is pivoted for vertical turning 75 movements in a standard 25 rising from the table 1, while its other end is slidably mounted in a standard 26 rising from the table 1. The block 22 and bar 23 are shown in the present instance as being prevented from turning by a bar 27 which projects loosely through a part of the clamping block 22, and has its ends secured in the block 24 and standard 26. The clamping block 22 is intended to act in opposition to the 80 guide-bar 2 in clamping and holding a piece of work in position while being operated on, and is freely movable with the bar 23 toward or away from the guide-bar 2. 85

In order to secure the clamping-block 22 and its bar 23 in clamped position, the bar 23 is preferably serrated longitudinally on its under side for a portion of its length, and coöperating with such serrated portion 90 is a serrated bar-holding member 28, which is mounted for vertical movements in a portion of the standard 26. The member 28 is carried by an eccentric portion 29 of a shaft 30 which is journaled in the standard 95 26 and has a lever arm 31 projecting from its outer end by means of which it is turned. It is apparent that a turning of the shaft 30 in one direction or the other will effect either a raising of the member 28 in holding 100 engagement with the bar 23 or a lowering of such member from bar holding position as desired. The shaft 30 is held within the standard 26 by a set-screw 32, the inner end of which fits within a peripheral groove in 105 a portion of the shaft. 110

The standard 26 is shown as being clamped to the table 1 by the engagement of the head of a clamping screw 33 with a flange on said standard, said screw being threaded into the table 1 and having one side of its head cutaway to adapt the screw to release said flange when the cutaway portion of its head has been turned into register with the flange, as is apparent. The purpose of securing the standard 26 in this manner to the table 1 is to facilitate an easy disengagement of the same from the table to permit a raising of such standard, the clamping block 22, and the bars 23 and 27 115 with the block 24 as the pivot thereof, to place said parts out of work obstructing position when desired. In the clamping of work to the guide-bar 2, the bar 23 is moved longitudinally to place the block 22 in 120 clamping engagement with the work in op- 125

position to said guide-bar, after which the lever 31 is moved to effect a raising of the bar holding member 28 in locking engagement with the serrated surface of the bar

5 23. The work is now clamped in position to be sawed, trimmed or otherwise acted on.

I wish it understood that my invention is not limited to any specific construction or arrangement of the parts except in so far as limitations are specified in the claims.

10 Having thus described my invention what I claim as new and desire to secure by Letters Patent is,—

15 1. In combination, a gage-block, a guide-bar for said block having a series of diagonally disposed teeth arranged longitudinally thereof, and means carried by the gage-block for coacting with said teeth to hold the gage-block in adjusted position

20 relative to the guide bar and being operable to effect an adjustment of the block intermediate the adjustment provided for by the bar teeth.

25 2. In a work gage, a guide-bar having a series of diagonally disposed teeth arranged longitudinally thereof and inclining from a plane which is transverse to the bar, a gage-block guided by said bar for reciprocal movements longitudinally thereof, a member movable with said block and having teeth for meshing with said bar teeth, and means for adjusting said member transversely of the bar.

30 3. In a work gage, a guide-bar having a surface thereof provided with a series of teeth which are angled relative to a plane transversely cutting the bar, a gage-block having a groove for receiving said bar to coöperate therewith to guide the movements 35 of the block, a member carried by said block and having teeth adapted to mesh with the bar teeth at any position of adjustment of the gage-block relative to the bar, and a screw threaded through said member and operative to move the member transversely 40 of the bar when in engagement with its teeth.

45 4. In a work gage, a guide-bar having a longitudinally extending series of diagonally extending teeth, a gage-block having a part fitting over said bar to permit the block to have shifting movements longitudinally of the bar, a screw rotatably mounted in said block and anchored against 50 longitudinal movements therein, a member threaded upon said screw and having teeth adapted to mesh with the guide-bar teeth when the gage block is mounted thereon, said member being adjustable transversely 55 of the guide-bar by a turning of said screw.

60 5. In a work gage, a guide-bar, a gage-block mounted for reciprocal movements on said bar longitudinally thereof, said bar and block having toothed portions capable of 65 meshing with each other and of having rela-

tive movements to effect an adjustment of the gage-block longitudinally of said bar when said parts are in mesh, the relative movements thereof being in intersecting planes.

6. In a work gage, a guide-bar having a series of longitudinally arranged teeth which extend diagonally thereof, a gage-block loosely mounted for reciprocal movements on said guide-bar, a member carried by said block for movements transversely of the guide-bar, a screw threaded through said member and mounted for rotary movements in said block, a bushing adjustably threaded into said block and forming a bearing for a part of said screw, and means coöperating with said bushing to prevent longitudinal movements of the screw relative to the block except when the bushing is rotated.

7. In a work gage, a guide-block having a series of teeth extending longitudinally of the bar and diagonally disposed relative thereto, a gage-block mounted for reciprocal movements on said bar, a screw carried by the block with its axis disposed transversely of said bar, means for adjustably anchoring the screw against longitudinal movements relative to said block, a member threaded upon said screw and having teeth for meshing with the guide bar teeth and adapted to coöperate therewith to effect an adjustment of the gage block longitudinally of said bar when said member is moved by a turning of the screw.

8. In an apparatus of the class described, a plate having a work stop thereon, a bar carried by said plate for longitudinal movements relative thereto, a clamping block fixed to said bar and movable therewith, said block being adapted to coöperate with said stop to hold work, and means for clamping said bar in adjusted position.

9. In an apparatus of the class described, a plate, a work stop mounted thereon, a standard rising from said plate, a bar longitudinally shiftable through said standard, a work clamping block carried by said bar and shiftable therewith, and means associated with said standard and movable to secure said bar in adjusted position or to release the same.

10. In an apparatus of the class described, a plate, a work stop mounted on the top thereof, a standard rising from the plate, a bar carried by said standard for longitudinal shifting movements, a work clamping block carried by said bar, a bar holding member associated with said standard, and cam means for moving said member into or out of bar holding position.

11. In an apparatus of the class described, a plate, standards rising from said plate, a block pivoted to one of said standards, a bar mounted for longitudinal movements

through said block and one of said standards, a work clamping block carried by said bar for shifting movements therewith, means associated with one of said standards for securing said bar in adjusted position, a bar connecting said pivoted block and one of said standards and coacting with the clamping block to prevent a turning of the shiftable bar and block, the said standard in 10 which the bars are mounted being capable

of being swung with said bars and clamping block out of work obstructing position with said pivoted block as their axis.

In testimony whereof, I have hereunto signed my name to this specification in the 15 presence of two subscribing witnesses.

FREDERICK W. ALBRECHT.
